United States Patent Office.

CHARLES W. GOODHUE, OF LOWELL, MASSACHUSETTS, ASSIGNOR TO EDWARD P. WOODS, DANIEL SHERWOOD, AND CYRUS H. LATHAM, OF SAME PLACE.

Design No. 4,977, dated June 6, 1871.

DESIGN FOR A NAPKIN-RING.

The Schedule referred to in these Letters Patent and making part of the same.

I, CHARLES W. GOODHUE, of Lowell, in the county of Middlesex and State of Massachusetts, have invented and produced a new and original Design for a Napkin-Ring, of which the following is a specification.

The nature of my design is fully represented in the accompanying drawing, to which reference is made.

General Description.

Figure 1 of the drawing represents a napkin-ring formed in accordance with my invention. It consists of a twisted-wire blank, Figure 2, and a metal band, Figure 3.

The blank is composed of two pieces of wire bent into the required shape, which can be seen by an examination of fig. 2, and then twisted together, as shown, in a machine. The ends of the blank are then twisted together so as to bring the blank into a cylindrical form, and after the required shape is given to the cylinder upon a mandrel the band, fig. 3, is slipped

on and the ends united by the plate or clasp shown in the completed ring, fig. 1.

A modification of the form of the blank is shown in Figure 4.

The wire for the body of the ring may be twisted up in any other way than that described and shown without varying or departing from my invention.

Claim.

I claim as my invention—

The design for a napkin-ring, shown in the accompanying drawing—that is to say, a napkin-ring made of wire, the ends scalloped or pointed, and the center mounted by a band or ring, substantially as described and specified.

CHARLES W. GOODHUE.
